H. M. McCORMACK & G. H. WALL.

LOGGING BUNK.

APPLICATION FILED OCT. 4, 1913.

1,098,580.

Patented June 2, 1914.

UNITED STATES PATENT OFFICE.

HARRY M. McCORMACK AND GEORGE H. WALL, OF SCOTIA, CALIFORNIA.

LOGGING-BUNK.

1,098,580.

Specification of Letters Patent.

Patented June 2, 1914.

Application filed October 4, 1913. Serial No. 793,436.

To all whom it may concern:

Be it known that we, HARRY M. McCORMACK and GEORGE H. WALL, citizens of the United States, residing at Scotia, in the county of Humboldt, State of California, have invented certain new and useful Improvements in Logging-Bunks; and we do hereby declare the following to be a full, clear, and exact description of the invention, such as will enable others skilled in the art to which it appertains to make and use the same.

The present invention is directed to improvements in logging bunks, and has for its object to provide devices of this character for use upon railway cars so constructed that the same may be easily released for dumping the logs.

A further object of the invention is to so construct devices of this character that when the chock plates are released the same will fall upon the car.

With these and other objects in view, this invention resides in the novel features of construction, formation, combination and arrangement of parts to be hereinafter more fully described, claimed and illustrated in the accompanying drawing, in which:

Figure 1 is a fragmentary plan view of a car equipped with bunks. Fig. 2 is a sectional view on line 2—2 of Fig. 1. Fig. 3 is a similar view on line 3—3 of Fig. 1. Fig. 4 is a view similar to Fig. 1, showing the chock blocks released. Fig. 5 is a detail perspective view of one of the chock plates. Fig. 6 is a similar view of a modified form of chock plate, the same being used preferably in connection with the innermost bunks.

Referring to the drawing, the numeral 1 designates the bottom of a logging car having bolted transversely thereof ties 2, upon the upper surface of which are bolted rails 3, said rails being held in spaced relation by blocks 4 and 5, the blocks 5 being arranged intermediate the ends of the rails 3. Passing through the rails 3 and blocks 5 are bolts 6, the eyes 7 of which are disposed upon opposite sides of the rails 3, similar bolts 8 being passed in opposite directions through the blocks 4. The eyes 9 of the bolts 8 are provided with sleeves 10, the purpose of which will appear later.

The chock plates 11 are formed from steel and comprise inclined inner and outer walls 12 and 13, respectively, the walls 12 having their lower edges provided with ears 14

which are adapted to engage between the rails 3. The lower edges of the walls 12 of the chock plates are provided with spaced ears 15 which are designated to engage the outer edges of the rail heads.

Secured to the corners of the walls 12 are the inner ends of the chains 16, said chains being passed through the eyes 7 of the bolts 6 and through the sleeves 10 carried by the eyes 9 of the bolts 8, the links of said chains being engaged by the hooks 17 which are flexibly connected to the ends of the ties 2, said hooks serving to hold the chock plates in adjusted positions.

The chock plates 18 operate in the same manner as the chock plates 11, but have their outer walls 19 provided with tongues 20 and their inner walls 21 provided with tongues 22 which are designed to engage between the rails 3. The outer ends of the chains 16 are provided with rings 23, which serve to prevent disengagement of the same from the sleeves 10, whereby when the load is released the chock plates will fall from the rails 3 on the bottom of the car, as shown in Fig. 4. Similarly connected chains are provided for the chock plates 18 and operate in the same manner as the chains 16. The eye bolts 6 and 8 not only serve as means for retaining the chains in their proper positions, but aid in strengthening the rails 3. By connecting the chains to the corners of the chock plates and securing the same to the hooks 17, the weight of the logs upon the plates will tend to swing the same laterally, thus causing the ears of the plates to bindingly engage the rails 3, and by so doing relieves the strain upon the chains so that the likelihood of the same breaking is eliminated.

From the foregoing description it will be seen that a logging bunk has been provided, which is exceedingly simple in construction, and one which can be easily and quickly applied to the conventional form of logging car.

What is claimed is:

1. The combination with a bunk provided with spaced rails, of chock plates comprising inclined walls, ears carried by the lower edges of the walls, and means connected to the corners of certain of the walls to swing the chock plates laterally when weight is applied thereon to cause the ears to bindingly engage the rails.

2. The combination with a bunk provided

with spaced rails, of chock plates comprising inclined inner and outer walls, ears carried by the lower central edges of the walls for engaging the sides of the rails, chains having their inner ends connected to the corners of the inner walls of the plates, means for attaching the outer ends of the chains to the bunks, whereby said chains serve in conjunction with the load to swing

the plates laterally to cause the ears to bind- 10
ingly engage the sides of the rails.

In testimony whereof, we affix our signatures in the presence of two witnesses.

HARRY M. McCORMACK.
GEORGE H. WALL.

Witnesses:

P. E. CARLAND,
CHARLES FRANCEE.
